United States Patent Office.

CONRAD SEIMEL, OF BROOKLYN, NEW YORK, ASSIGNOR TO CHARLES PRATT, OF NEW YORK CITY.

Letters Patent No. 96,274, dated October 26, 1869.

IMPROVEMENT IN OIL-CAN STOPPERS.

The Schedule referred to in these Letters Patent and making part of the same.

To whom it may concern:

Be it known that I, CONRAD SEIMEL, of Brooklyn, in the county of Kings, and State of New York, have invented certain new and useful Improvements in Stoppers for Oil-Cans and other vessels; and I hereby declare the following to be a full, clear, and exact description of the same, reference being had to the accompanying drawings, in which—

Figure 1 is a perspective view of an oil-can, provided with my improved stopper.

Figure 2 is a vertical section of the same.

It is well known that the use of cans and small vessels for distributing oils and other fluids has become very general within the last few years.

When these cans or small vessels are used, great difficulty is experienced in emptying them without spilling some of the contents, resulting principally from the fact that there has been no vent or conduit for admission of air to the can while the liquid is being poured out. To remedy this difficulty, vent-nozzles or other like devices have heretofore been used with cans or vessels, but such appliances have always been costly, and their use has been attended with inconvenience, while they require cans of special construction, and, indeed, are permanently united with and form part of the cans.

My object is to furnish a device of this kind, which is simple of construction, and can be readily and cheaply made, which may be readily removed from or applied to the can, and used with any can of ordinary or suitable construction, and which may be manufactured and sold as a distinct article, and not necessarily accompanying the can. To this end,

My invention consists of a stopper for oil-cans or other liquid-holding vessels, (for whatever use,) provided with an opening or spout for outflow of the liquid, in combination with a vent for the passage of the air.

The manner in which this device can be constructed and used will be readily understood by reference to the accompanying drawings.

The stopper, there represented as closing the mouth of the can, is composed of the cork or other body *a*, of suitable material, which carries the tube or spout *b* for outflow of the liquid, and the smaller tube or vent *c*. This device can therefore be applied to or

removed from the vessel, as shown in the drawing, just as an ordinary stopper.

The two tubes *b* *c* pass down through the cork and open into the interior of the vessel, and the smaller or vent-tube is arranged upon one side of and so as to follow the curve of the larger tube, and so that when the vessel is tipped to pour the liquid, the larger tube will be beneath, by which arrangement the oil or fluid will flow, only through the tube *b*, leaving the vent free.

The tubes are in this instance held to the cork by means of the metal disks *d* *d*, which are soldered to the tubes at such distance apart as to compress the body of the cork between them, the turned-up edges of the disks entering the cork and holding it tightly. Instead of this construction, the tubes may be held in other ways, and the body *a* of the device may be formed of the cork or of any other suitable material capable of closing the orifice in the can; and it may even be of metal, which can be screwed into or upon the neck of the can.

In any event, however, a detachable stopper will be obtained, in which the spout or opening for outflow is combined with a vent, and this device can be applied to any can, vessel, or receptacle for liquids, whatever its shape or size, provided that such receptacle be provided with a neck or mouth, into which the stopper can be fitted.

Having now described my invention, and the manner in which the same is or may be carried into effect, What I claim, and desire to secure by Letters Patent, is—

1. A stopper for oil-cans, or other receptacles for liquids, provided with an opening or spout for outflow of the liquid, in combination with a vent-opening or tube, substantially as shown and described.
2. The combination of the body of the stopper with the vent and outflow-tubes, and the disks for holding the body and tubes together, substantially as shown and set forth.

In testimony whereof, I have signed my name to this specification, before two subscribing witnesses.

Witnesses: CONRAD SEIMEL.
